UNITED STATES PATENT OFFICE.

CARY COOK, OF COVINGTON, GEORGIA.

MAIL-BOX SUPPORT.

Application filed July 25, 1923. Serial No. 653,771.

To all whom it may concern:

Be it known that I, CARY Cook, a citizen of the United States, and resident of Covington, county of Newton, and State of Georgia, have invented an Improvement in Mail-Box Supports, of which the following description, in connection with the accompanying drawings, is a specification, like characters on the drawings representing like parts.

This invention has reference to mail box supports for use on rural routes and this application is, in part, a continuation of my copending application Serial Number 550,1544, filed April 7, 1922, for "Mail box supports." The invention aims to provide an adjustable support which may be shipped collapsed and easily erected by anyone in proper supporting position on any contour 20 of ground. However, it will be understood that it is capable of other uses.

Among the advantages of my invention are its simplicity and strength, and its ready adjustment in any one of a plurality of positions to hold a mail box or other receptacle at a suitable height from the road and at a convenient distance for delivery of mail or other articles by the carrier without driving off of the road. Other objects and advantages will appear in the specification when considered in connection with the accompanying drawings, wherein:

Figure 1 is a side elevation of one form of my improved support, disclosing one position thereof in dotted lines;

Fig. 2 is a front elevation of the support taken from the left of Fig. 1, and

Fig. 3 is a sectional view on the line 3—3 of Fig. 1.

In the illustrative embodiment of my invention shown in the drawings, wherein all the parts are preferably, though not necessarily, made of metal, I have provided a base or anchor member 1 preferably formed of sheet metal, such as boiler plate, for example, and having a wing member 2 thereon, which may be formed by slitting and bending a portion of the anchor plate at right angles as shown clearly in Fig. 3, and also 50 preferably having the lower end 3 bent at right angles to the plane of the anchor to prevent lateral displacement thereof when it is imbedded in the ground, in concrete, or in gravel, as shown in the drawings.

At the upper end of the anchor, a plurality of holes 4 are punched to afford means

for adjustably connecting and supporting a standard thereon. These holes may advantageously be arranged in two parallel rows as shown in Fig. 1, although other arrangements will suggest themselves as suitable for special purposes.

My improved standard preferably comprises a lower section 5 of flat merchant bar having a bolt hole near its lower end whereby it may be pivotally connected to the base 1 by means of a pin or bolt 6 engaging one of the openings 4. A plurality of holes 7 are punched at spaced intervals along the length of the section. An upper section 8, preferably of the same material as the lower section and also having a plurality of bolt holes 9 spaced the same as the openings in the lower section 5, is adapted for connection to the lower section 5 by suitable fastenings, such as the bolts 10. Thus the height of the standard may be varied by raising or lowering the upper section and rigidly securing the two sections together by means of the pins or bolts 10 passing through registering openings therein (Fig. 1).

A platform 11 is provided for supporting the mail box or other receptacle. This platform is preferably made of a T-shaped iron bar as shown in Fig. 2 and has a row of spaced openings 12 throughout its length adapted to register with the top opening in the section 8 of the standard whereby it is pivotally mounted in suitable adjusted position. Horizontal adjustments of the supporting platform with respect to the standard may be made by securing it thereto through any one of the openings 12. The cross flange of the T-bar is preferably provided with suitable openings or notches (not shown) to receive the usual screws or bolts for attaching a box or receptacle thereon, in a well known manner.

In order to support the standard rigidly upon the anchor 1, in proper angularly adjusted positions, a suitable brace 14, preferably made of rod iron having its ends bent at right angles and screw threaded, is adapted to be secured at one end in any one of the openings 4 in the anchor and at the other end in one of the openings 7 in the standard member 5 by nuts 15 cooperating with the threaded bent ends. Thus, the standard is capable of adjustment through a range of approximately 180°.

The platform 11 may be supported rigidly in horizontal position by a bracket or brace

16, similar to the brace 14, which is designed to be secured at one end in any one of the openings 12 therein and at the other end in one of the openings 9 in the standard section 8.

My improved extensible standard is susceptible of a considerable range of angular adjustment with respect to the anchor member by reason of the arrangement of the 10 openings in the anchor and the standard. For example, if it is desired, the standard may be adjusted to a horizontal position on either the right or left side of the anchor as seen in Fig. 1, by securing the lower section 5 of the standard in the proper opening 4, (one of the lower openings for example) and then inserting the brace rod 14 in the proper openings in the anchor and standard. If it should be necessary to place the standard 20 on a steep incline, the anchor member may be set in the ground in an angular position, and the standard may be adjusted thereon with equal facility.

It is frequently necessary to set the anchor on one side of the road gutter, as shown in Fig. 1 for example, to avoid making an obstruction to road repairs; in which case it is desirable, for the convenience of carriers, to support the mail box in a projected 30 position over the road bed. My improved standard may be extended over the road to the regulation height required by the Post Office Department by suitably adjusting it angularly with reference to the base and the 35 box supporting platform 11 may be secured thereto at a suitable angle to hold it in a horizontal position as indicated in Figure 1. Also, if desired, the box supporting platform may be adjusted horizontally on the support to project the box in either direction after the standard is secured in adjusted position. Thus, the standard may easily be set to support the box in the most 40 convenient position for a carrier.

Obviously, the brace rod 16 for the supporting platform 11 is adapted to cooperate with any one of the openings 12 therein, on either side of the standard, as viewed in Figure 1. Thus, it is possible to set the 50 supporting platform at any desired angle with respect to the standard.

Another important advantage of the pivotal connection between the standard and the anchor member, is, that it enables an 55 ordinary unskilled laborer to remove the brace rod 14 either from the standard or from the anchor and swing the standard away from its position over the edge of a road bed. This may be necessary at infrequent intervals, during road repairs and is 60 easily and conveniently accomplished. After the road work is completed, the standard may be again set in its original adjusted position by securing the brace rod 14 in the 65 hole from which it was withdrawn.

Still another advantage of my invention resides in the fact that all of the parts may be made of commercial steel strips, bars or shapes, fabricated by cutting and punching operations, thus reducing the cost to a minimum.

A plurality of boxes may be supported upon a single standard, if desired, in which case it is only necessary to secure a wide board or other strip in the usual way to the supporting element 11 and attach the boxes thereto.

Obviously my invention is not limited to the specific embodiment herein described but is susceptible of various changes.

Having thus shown and described one illustrative embodiment of my invention without restricting myself thereto, what I claim and desire to secure by Letters Pat-

1. A mail box support comprising, in combination, a base adapted to be anchored in the ground, a standard pivotally mounted for angular adjustment in a vertical plane on said base, a box supporting means 90 adjustably mounted on said standard and means whereby said box supporting means may be secured in a horizontal position on the standard for all positions of angular adjustment of the standard.

2. A mail box support comprising, in combination, a base adapted to be anchored in the ground, an extensible standard pivotally mounted on said base and adapted to be secured in different angular positions with respect thereto, a box supporting member adjustably mounted on said standard and means for securing said member in a horizontal position on said standard.

3. A mail box support comprising, in combination, a standard pivotally mounted on a support for angular adjustment in a vertical plane, and a box supporting member connected to said standard for angular adjustment in a vertical plane and for horizontal adjustment with respect thereto.

4. In a support for mail boxes and the like, an anchor member, a standard pivotally mounted on said anchor member; a brace on the anchor member adapted to hold the standard in angularly adjusted positions and an adjustable box supporting member adapted to be secured in a horizontal position on the standard for all positions of adjustment of the standard.

5. A support comprising, in combination, an anchor member adapted to be imbedded in the ground, an extensible standard mounted for angular adjustment with respect to the anchor and adjustably secured thereto, a supporting member mounted on the standard for angular adjustment with respect thereto and being capable of horizontal adjustment thereon, and means for maintaining said standard and supporting

member in any desired position of adjustment.

6. A support for mail boxes and the like comprising, in combination, an anchor 5 adapted to be imbedded in the ground, an extensible standard mounted for angular adjustment on said anchor member, means cooperating with said standard and anchor member to secure said standard rigidly in 10 any one of a plurality of angularly adjusted positions and a box supporting platform mounted on the upper end of said standard and adapted to be secured rigidly thereto in a horizontal position for all positions of 15 adjustment of the standard.

7. A support for mail boxes and the like comprising, in combination, a sheet metal anchor member having a plurality of holes near its upper end, a standard pivotally connected to said anchor member in one of said holes, a brace secured to said standard and adapted to be secured in any of the remaining holes in the anchor member to support the standard rigidly in any one of a plurality of angularly 20 adjusted positions and a box carrier mounted on said standard adapted to be adjusted thereon to a horizontal position for all positions of adjustment of the standard.

8. A support for mail boxes comprising, in combination, a sheet metal anchor having lateral wings thereon adapted to be imbedded in the ground, an extensible standard mounted on the upper end of said anchor, means for securing said standard to said anchor in any one of a plurality of angularly adjusted positions with respect to the plane of the ground and adjustable box supporting means mounted on the upper 35 end of the standard.

9. In a support for mail boxes, a base member having a flat upper end and pro-

vided with a plurality of spaced openings arranged in longitudinal rows therein, a standard having a plurality of longitudinally spaced openings therein adapted to be pivotally mounted on said anchor member in any one of the openings in said anchor member, a brace for said standard adapted to cooperate with one of the openings therein and one of the openings in the anchor member to secure the standard in one of a plurality of angularly adjusted positions and a box supporting member pivotally mounted on the upper end of said standard and adapted to be secured thereto in horizontally adjusted positions for all 45 positions of adjustment of the standard.

10. A mail box support comprising, in combination, an anchor member adapted to be imbedded in the ground at an angle to the vertical, a standard connected for relative angular adjustment to said anchor member, said anchor and said standard having openings therein, means cooperating with said openings to secure said standard rigidly to said anchor in any one of a plurality of relative angular positions of adjustment, the height of said standard being adjustable, and box supporting means on said standard.

11. A mail box support comprising the anchor 1, the extensible standard elements 5 and 8 adjustably and pivotally secured thereto, the box supporting platform 11 adjustably supported on the upper end of the standard element 8, and the brace rods 14 and 16 for rigidly supporting said platform and standard, all substantially as shown and described.

In testimony whereof, I have signed my name to this specification.

CARY COOK.
